UNITED STATES PATENT OFFICE.

BENJAMIN HANDFORTH, OF CHICAGO, ILLINOIS.

IMPROVED CURTAIN-FIXTURE.

Specification forming part of Letters Patent No. **59,009**, dated October 23, 1866.

To all whom it may concern:

Be it known that I, BENJAMIN HANDFORTH, of Chicago, in the county of Cook and State of Illinois, have invented a new and useful Improvement in Curtain-Fixtures; and I do hereby declare and make known that the following is a full, clear, and exact description of the same, reference being had to the accompanying drawings, and the letters and figures marked thereon, which form part of this specification.

To enable those skilled in the art to construct and use my invention, I will proceed to describe the same with particularity, making reference in so doing to the aforesaid drawings, in which—

Figure 1 represents a front elevation of my invention; Fig. 2, a side view of the same; Fig. 3, a detached view of the sheave or grooved roller E, and Fig. 4 a transverse section of the roller R.

My said invention consists, first, in a novel arrangement whereby the curtain may be raised and lowered and secured in any desired position; second, in a novel support or bearing for the roller, upon which the curtain or shade is arranged, whereby the same may be used with equal facility upon the right or left hand side of the window; and, third, in a novel mode of securing the curtain or shade to the roller upon which it is wound or rolled up.

A represents any ordinary curtain or shade, secured to a roller, R, as hereinafter described, which is sustained in suitable bearings or supports at each end, one of said supports, B, being provided with a socket, into which one end of the roller enters, and the other support being provided with an open slot, c, upon which the other end of the said roller R is laid, as seen in Fig. 2, there being a similar slot, c', upon the lower side of said support C, so that said support may be arranged in an inverted position upon the opposite side of the window with equal facility and advantage.

The roller R is divided longitudinally in two parts, between which is arranged the curtain A, as shown in Fig. 4, and is secured to said roller by means of the bolts, screws, or rivets s, or their equivalent. The drawings represent the roller as being divided into two equal parts; but this is not necessary, as any two parts fastened together in substantially the same way would answer the same purpose.

I am aware that the curtain has been fastened to the roller by having a groove arranged upon said roller, and securing the curtain therein by forcing a corresponding strip into said groove; but from the fact that the thickness of curtains vary, in many instances the said strip fits so loosely into the groove as to afford no reliable means of fastening the curtain to the roller, and sometimes it will not enter at all without being diminished in diameter, and therefore this mode of securing the curtain to the roller is very inconvenient and undesirable; whereas by my method above described the operation is always sure, effectual, and reliable.

D represents a cord, one end of which is secured to the roller R, and the other, passing under the grooved wheel or sheave E, hangs down so as to be readily reached when desired.

When the curtain is drawn down the said cord is wound upon the roller, so that by pulling upon said cord the curtain is rolled up. When the cord D is held in such a position as to lie under or in the groove a, it slides or moves freely; but upon being drawn in toward one side and slackened slightly, the retrograde movement of the said roller E draws the cord into an oblique groove, b, opening out from the groove a, and running out toward the surface, so as to gradually become shallower toward its outer end, and thus wedges or secures the cord to the face of the window-casing and holds the curtain in the position desired. When the curtain is to be readjusted, a slight pull upon the cord will disengage it, when it is held parallel with the groove a and operates as before.

Having described the construction and operation of my invention, I will now specify what I claim and desire to secure by Letters Patent:

In combination with the curtain A, roller R, and cord D, the arrangement of the sheave E, provided with the groove a and one or more oblique grooves, b, operating substantially as and for the purposes specified.

BENJN. HANDFORTH.
